COMBINED SIGHTING DEVICE AND AUTOMATIC PROJECTILE-RELEASER FOR AIR-VEHICLES.

1,130,621.

Specification of Letters Patent.

Patented Mar. 2, 1915.

Application filed October 30, 1913. Serial No. 798,381.

To all whom it may concern:

Be it known that I, LUDWIG MANDELARTZ, residing at Essen-on-the-Ruhr, Germany, a subject of the Emperor of Germany, have 5 invented a certain new and useful Improvement in Combined Sighting Devices and Automatic Projectile-Releaseers for Air-Vehicles, of which the following is a specification.

10 The present invention relates to a combined sighting device and automatic projectile releaser used on air vehicles, especially on flying machines, which device makes it possible to automatically drop the 15 projectile, as soon as the correct distance from the target is reached, when the sighting device has been adjusted to correspond to the altitude of the flying machine and to its speed; and the sight line, with this adjustment during its flight, is constantly kept 20 directed on the target.

In sighting devices of the prior art, the controlling member of the releaser at the moment of dropping a projectile, may have 25 quite different positions. If therefore the observer, when using the sighting devices of prior art does not constantly keep his attention, during the entire observation time, on an exact crossing over the target, he 30 must then look away from the target to ascertain, when the moment for dropping a projectile approaches.

The subject matter of the present invention is now a sighting device of the kind referred to in the beginning of this application, by the use of which, the observer may feel from the position of the handle of the releaser, when the moment for dropping a projectile approaches; so that he continuously 35 may keep the target in sight, without, however, having to keep rigid attention, during the entire time of observation, on an accurate crossing over the target for the moment to act.

40 In the accompanying drawing is illustrated one embodiment of the invention and Figure 1 shows a longitudinal section through the portion of a flying machine, which contains the sighting and releasing device; 45 Fig. 2 a section along line 2—2 of Fig. 1, seen from the left. The following figures are in larger scale and Fig. 3 shows a section along line 3—3 of Fig. 1 seen from the right; Fig. 4 a rear view, partly in section

of the sighting device, as well as a portion 55 of the releaser with the parts in different position; Fig. 5 a side view of Fig. 4 with the parts in the position shown in Fig. 1 and Fig. 6 a section along line 6—6 of Fig. 4, seen from the left.

60 Side by side with the seat A¹ of the air ship pilot, see Fig. 2, is provided a seat A² for the observer, whose duty is to attend to the sighting and releasing device. In front of the seat A² is mounted a cross shaft B in 65 bearings on the chassis A of the flying machine, which shaft, by means of bevel gears b¹ c¹, has driving connection with a longitudinal shaft C, also mounted in bearings on the chassis of the flying machine. A 70 projectile D is, by means of a hook d¹, suspended from the shaft C, the axis of which is situated in the central, longitudinal plane of the flying machine. The hook d¹ and the portion of the shaft C embraced by the hook, 75 see Fig. 3, have such shape, that the hook will lose its hold on the shaft C, as soon as the latter is turned in a certain angular position. For this purpose the end of the hook d¹ barely reaches the center line at the top 80 of the shaft C, and the shaft itself is cut down to a smaller diameter at the place where it engages with the hook d¹, indicated by dotted lines in Fig. 1. The diminished portion of the shaft is moreover cut away on 85 one side along an axial plane of the shaft, so that the shaft has a flat surface of the same width as the smaller shaft diameter. The hooks can consequently never engage more than a quadrant of the shaft and will 90 be released as soon as the flat surface stands vertical. In Fig. 3 the larger circle represents the main diameter of the shaft.

95 On a projecting sleeve e¹, Fig. 4, of a bearing E for the shaft B, is revolvably mounted a two armed lever, the one arm F of which is provided with a handle f¹, and the other arm F² carries an arc f³ curved concentric with the shaft B. On the arc f³ is guided a slide G, which may be displaced 100 along the arc by means of a spiral gear g¹ seated on said slide engaging with corresponding teeth f⁴ of the arc f³. On the shaft B and coaxial with the hand lever F f¹ F², is revolvably mounted a crank lever, whose 105 arm H carries a transversely adjustable telescopic sight J. The other arm H¹ of the crank lever, carries an arc h², curved co-

axially with the shaft B, which arc slides in a guide piece G³, rigidly connected with the slide G through its arm g², and may be displaced by means of a spiral gear g⁴ meshing 5 with teeth h³ of the arc h² and mounted on the guide piece G³. The gearing g¹ f⁴ serves to impart a main adjustment of the sight line relative to the hand lever F f¹ F² while the gearing g⁴ h³ serves for adjusting corrections. For reading the main adjustment 10 is provided an angular scale, not shown, on the back of the arc f³ and a mark on the slide G. Similarly is provided on the back of the arc h² a correcting scale, not shown, and a corresponding reading mark on the 15 guide piece G³.

In the hub of the handle F f¹ F² is provided a cut f⁵ engaging with a coupling pin b² secured in the shaft B and extending 20 through a slot e² of the projecting sleeve e¹. As a result of this arrangement, the hand lever F f¹ F², when turned in the direction of lowering the sight line, that is, in the direction of arrow x, is coupled with the shaft B, as soon as the face f⁶ of the cut f⁵, which 25 face is located to the rear during said movement, impinges against the coupling pin b². The shaft B is influenced by a spiral spring K located in the bearing E, which spring tends to turn the shaft B in opposite direction 30 of the arrow x and the shaft C in the direction of the arrow y, by means of the selected bevel gears b¹ c¹ shown in the drawing. The relations are selected so that the 35 shaft C is situated on such angular position, when the coupling pin b² impinges against the end designated by e⁸ of the slot e², that the release of the projectile is effected; and that when the coupling pin b², actuated by 40 the pressure of the spring K, impinges against the other end of the slot e², the shaft C has the angular position illustrated in Fig. 3, wherein the hook d¹ is supported on the shaft C. The length, measured circumferentially, of the cut f⁵ is made as large 45 as possible, so that the sight line, without changing its adjustment in elevation, given by the gearing g¹ f⁴ and g⁴ h³, may be oscillated within the greatest possible limits. 50 The length of the slot e² has on the contrary been selected as small as possible, in order to diminish as much as possible, the angular range, within which the oscillation of the sight line in the direction of the arrow x only follows by simultaneous turning 55 of the shaft B while overcoming the resistance of the spring K.

The angular scale provided on the back of the arc f³, must be so arranged, that, with 60 each adjustment of the slide G, the mark thereon indicates the angle, which the sight line (being in its middle position relative to the side direction) forms with the middle, longitudinal axis of the flying machine, 65 when the mark of the guide piece G³ regis-

ters with the zero-point of the correcting scale provided on the arc h², and the hand lever F f¹ F² has simultaneously been turned so far in the direction of the arrow x, that the coupling pin b² impinges against the 70 end e⁸ of the slot e². The position of the lever arm F f¹, which corresponds to said 75 positions of the coupling pin b² and the hand lever F f¹ F², has been indicated by dot and dash lines in Figs. 1 and 5.

When a target is to be hit by a projectile thrown off from a moving flying machine, the sight line, directed against the target, must evidently form a certain angle with the horizontal line at the moment of ejection. The magnitude of this angle, which in the following will be called "sighting angle" depends only on the speed of flight and the altitude of flight, not taking into account secondary influences such as wind, 80 height of barometer, etc. The sighting angle may be easily ascertained, by, for instance, the assistance of a table, when the speed of flight and altitude of flight are known. In using the here described device, 85 the slide G is now so adjusted by means of the gears g¹ f⁴, that the mark thereon registers with the division line of the angular scale provided on the arc f³, which line corresponds to the sighting angle. Necessary 90 corrections may be made by means of the gears g⁴ h³ through displacement of the arc h² relative to the guide piece G³. If the lever arm F f¹ were turned to the angular 95 position indicated by dot and dash lines 100 while the middle, longitudinal axis of the flying machine remains constantly horizontal during the flight, as has herein been supposed, the sight line would, in consequence 105 of the above named adjustment, form an angle against the horizontal line, which is equal to the adjusted sighting angle, or equal to the angle, which the sight line, directed on the target, forms with the horizontal 110 line, when the flying machine has reached the required distance from the target, to hit the latter.

Should the sight line be directed against the target, when the flying machine is at greater distance from the target, the sight 115 line will then form an angle with the horizontal line, which is considerably smaller than the above named angle. The lever arm F f¹ will thereby generally occupy such a great angular distance from its extreme position indicated by the dot and dash lines, and in opposite direction to the arrow x, that the limiting face f⁶ of the cut f⁵ not yet 120 impinges against the coupling pin b² of the shaft B. This has the advantage, that the handlever F f¹ F² together with the crank lever H H¹ and the telescopic sight J may be turned quite freely within certain limits, whereby the directing of the sight line 125 against the target is facilitated. While the 130

flying machine is nearing the target, the observer, continually turning the handlever $F^1 F^2$ in the direction of the arrow x , keeps the sight line constantly directed against the target. As soon as the limiting face f^4 of the cut f^5 , during this turning of the hand lever, has impinged against the coupling pin b^2 , the shaft B will follow in the turning of the hand lever, and the shaft C will turn in opposite direction to the arrow y , that is, in the direction to release the projectile. When finally the flying machine has attained the distance required to hit the target, and the sight line directed on the target then forms an angle with the horizontal line, which is equal to the sighting angle, the lever arm F^1 will then simultaneously have arrived in its extreme position indicated by dot and dash lines and the same instant the release of the projectile will take place. If now the hand lever $F^1 F^2$ is set free, the shaft C will return, actuated by the spring K , to its original position shown in Fig. 3, so that a new projectile may be suspended therefrom.

From the above given description it will be evident that the hand lever $F^1 F^2$ always has the same position at the instant of releasing the projectile for all values of speed or altitude of flight. The observer may therefore already by feel and without leaving the target out of sight, know when the releasing moment is approaching, which constitutes the advantage of this invention as set forth in the beginning of this specification.

In place of the mechanical projectile releasing device of the described embodiment, an electrical releasing device may naturally be used, which for instance could be brought into action, so that the hand lever $F^1 F^2$ closes or opens an electric circuit, when it has attained a certain angular position.

In the case that the flying machine before the dropping of the projectile, always travels with the same actual speed, the angular scale provided on the back of the arc f^3 may be substituted by a corresponding scale of altitude of flight, as in this case the sighting angle is dependent only on the altitude of flight when the secondary influences, compensated for by means of the gears $g^4 h^3$, are not considered.

I claim:

1. A combined sighting and projectile releasing device for air vehicles having a sight carrier, a movable releaser causing the projectile to drop when assuming a predetermined position and means for locking said sight carrier and releaser together in different positions corresponding to the desired sighting angles.

2. A combined sighting and projectile releasing device for air vehicles, having a revoluble sight carrier and a revoluble pro-

jectile releaser and means for locking said carrier and releaser together in different angular positions, a common horizontal shaft for said carrier and releaser.

3. A combined sighting and projectile releasing device for air vehicles, having a revoluble sight carrier, and a revoluble projectile releaser and means for locking said carrier and releaser together in different angular positions, a common horizontal shaft for said carrier and releaser; said releaser constructed to release a projectile when in a certain angular position.

4. A combined sighting and projectile releasing device for air vehicles, having a revoluble sight carrier and a revoluble projectile releaser and means for locking said carrier and releaser together in different angular positions, a common horizontal shaft for said carrier and releaser; said locking means comprising an arcuate arm on said carrier, and another arcuate arm on said releaser, both arms concentrically curved around the axis of said shaft, a slide with suitable guide ways slidably engaging said arcuate arms respectively, and gearing for slidably displacing said slide relative to each of said arms.

5. A combined sighting and projectile releasing device for air vehicles, having a revoluble sight carrier and a revoluble projectile releaser and means for locking said carrier and releaser together in different angular positions, a common horizontal shaft for said carrier and releaser; said releaser comprising a bearing for said shaft having a short circumferential slot and a stud in the shaft extending through said slot, and permitting a limited oscillation of the shaft, a spring tending to turn said shaft into its normal position of supporting a projectile.

6. A combined sighting and projectile releasing device for air vehicles, having a revoluble sight carrier and a revoluble projectile releaser and means for locking said carrier and releaser together in different angular positions, a common horizontal shaft for said carrier and releaser; said releaser comprising a bearing for said shaft having a short circumferential slot and a stud in the shaft extending through said slot, and permitting a limited oscillation of the shaft, a spring tending to turn said shaft into its normal position of supporting a projectile, a lever connected with said locking means, a hub for said lever mounted on said bearing and being provided with a long circumferential cut adapted to engage with said stud at a certain angular position of said lever, whereby said lever may have a partial oscillation independent of said shaft.

7. A combined sighting and projectile releasing device for air vehicles, having a revoluble sight carrier and a revoluble pro-

4

jectile releaser and means for locking said carrier and releaser together in different angular positions, a common horizontal shaft for said carrier and releaser; said releaser comprising a bearing for said shaft having a short circumferential slot and a stud in the shaft extending through said slot, and permitting a limited oscillation of the shaft, a spring tending to turn said shaft into its normal position of supporting a projectile, a lever connected with said locking means, a hub for said lever mounted on said bearing and being provided with a long circumferential cut adapted to engage with said stud at a certain angular position of said lever, and means actuated by said shaft for supporting a projectile when the shaft stands in normal position and release the projectile when said shaft has been turned into its extreme opposite position.

8. A combined sighting and projectile releasing device for air vehicles, having a revoluble sight carrier and a revoluble projectile releaser and means for locking said carrier and releaser together in different angular positions, a common horizontal shaft for said carrier and releaser; said releaser comprising a bearing for said shaft having a short circumferential slot and a stud in the shaft extending through said slot, and permitting a limited oscillation of the shaft, a spring tending to turn said shaft into its normal position of supporting a projectile, a lever connected with said locking means, a hub for said lever mounted on said bearing and being provided with a long circumferential cut adapted to engage with said stud at a certain angular position of said lever, and means actuated by said shaft for supporting a projectile when the shaft stands in normal position and release the projectile when said shaft has been turned into its extreme opposite position; said locking means comprising an arcuate arm on said carrier and another arcuate arm on said releaser, both arms concentrically curved around the axis of said shaft, a slide with suitable guide ways slidably engaging said arcuate arms respectively, and gearing for slidably displacing said slide relative to each of said arms.

9. A combined sighting and projectile releasing device for air vehicles, having a revoluble sight carrier and a revoluble projectile releaser and means for locking said carrier and releaser together in different angular positions, a common horizontal shaft for said carrier and releaser; said releaser comprising a bearing for said shaft having a short circumferential slot and a stud in the shaft extending through said slot, and permitting a limited oscillation of the shaft, a spring tending to turn said shaft into its normal position of supporting a projectile, a lever connected with said locking means, a hub for said lever mounted on said bearing and being provided with a long circumferential cut adapted to engage with said stud at a certain angular position of said lever, and means actuated by said shaft for supporting a projectile when the shaft stands in normal position and release the projectile when said shaft has been turned into its extreme opposite position; said locking means comprising an arcuate arm on said carrier and another arcuate arm on said releaser, both arms concentrically curved around the axis of said shaft, a slide with suitable guide ways slidably engaging said arcuate arms respectively, and gearing for slidably displacing said slide relative to each of said arms; and suitable scales for reading the angular setting of said carrier and releaser.

The foregoing specification signed at 85 Barmen, Germany, this 9th day of October, 1913.

LUDWIG MANDELARTZ. [L. S.]

In presence of—
 HELEN NUFER,
 ALBERT NUFER.
